UNITED STATES PATENT OFFICE

101,729

DESIGN FOR A SCRATCH BRUSH

Frederic J. Bickel, Cleveland, Ohio, assignor to
The Osborn Manufacturing Company, Cleve-
land, Ohio, a corporation of Ohio

Refiled for abandoned application Serial No.
47,114, February 6, 1933. This application
February 11, 1936, Serial No. 61,096

Term of patent 7 years

To all whom it may concern:

Be it known that I, Frederic J. Bickel, a citizen of the United States and a resident of Cleveland, county of Cuyahoga, and State of Ohio, have invented a new, original, and ornamental Design for a Scratch Brush, of which the following is a specification, reference being had to the accompanying drawing, forming a part thereof. This application is a substitute for my prior application Serial No. 47,114, filed February 6, 1933 for "Brush".

In the accompanying drawing:

Fig. 1 is a perspective view of a scratch brush showing my new design;

Fig. 2 is a side elevation; and

Fig. 3 is a section on the plane 3—3, Fig. 2.

The characteristic features of my design reside in a handle having a long graceful sweeping reverse curve on the top and bottom surfaces of said handle, said top and bottom forming converging convex surfaces at the rear of said handle both of which terminate in an abrupt vertical plane and the top being turned sharply downward at the forward end.

The shading indicates contrasting light and shade effects.

What I claim is:

The ornamental design for a scratch brush substantially as shown and described.

FREDERIC J. BICKEL.
